UNITED STATES PATENT OFFICE.

CLARENCE D. HESS, OF NEW YORK, N. Y., ASSIGNOR TO CLARENCE GROVER HESS, OF SAME PLACE.

TRAVELING-TRUNK.

SPECIFICATION forming part of Letters Patent No. 367,979, dated August 9, 1887.

Application filed February 4, 1887. Serial No. 226,531. (No model.)

To all whom it may concern:

Be it known that I, CLARENCE D. HESS, a citizen of the United States, residing at New York, in the county of New York and State 5 of New York, have invented a new and useful Improvement in Traveling-Trunks, of which the following is a specification.

My invention relates to traveling-trunks, and has for its object the provision of means 10 whereby a traveler shall have easy access to any special article within a trunk without disturbing any other of the contents or detaching any portion of the trunk.

My invention further consists in the provision 15 of means whereby the body of an ordinary traveling-trunk is convertible into a bureau and toilet dressing-case.

My invention further consists in a novel and peculiar construction of the trunk-cover, 20 whereby it is adapted for use as an office-desk or escritoire.

In furtherance of my object my invention contemplates dividing both the trunk-body and its cover into compartments, each division 25 provided with locking and closing devices, whereby said compartments can be independently closed and locked, and in combinations of various of the devices, all as herein more particularly described, illustrated in the drawings, and specifically pointed out in the claims.

Referring to the accompanying drawings, in which like letters of reference point out similar parts on each figure, Figure 1 is a perspective view of a closed trunk embodying 35 my invention. Fig. 2 is a like view showing the trunk standing on end. Fig. 3 represents the trunk as shown in Fig. 2 thrown open, all the compartments being securely closed, the hinged end of the trunk thrown up, dis- 40 closing the hinged lid of the toilet-division. Fig. 4 is a view of the trunk in like position, showing the toilet-case lid lifted up, the escritoire open, and the locking-bar removed from bureau-drawers, parts being broken away.

Fig. 5 is a sectional view on the line xx , Fig. 4. Fig. 6 is a detached view showing means of interlocking and releasing the cover of the pigeon-holes and the stationery-drawer. Fig. 7 is a detached view of the locking-bar. 45 Fig. 8 is a detail view showing construction 50 of the pigeon-holes and their spring-pressed

boards. Fig. 9 is a diagrammatic view of the toilet compartments with divisional partitions.

In the drawings, A is the trunk-body; A', its cover; a, the lock; a'a', clasps or bolts; a², 55 handles common to such articles.

B is the hinged end of the trunk, provided with flanges b b, for a purpose presently set forth, the opposite end, B', being permanently closed.

C is the toilet-compartment, its two side walls being formed of part of the front and rear of the trunk-body, its back being part of the trunk-bottom. (See dotted lines, Fig. 1.) Its front is a rigid strip, c, permanently attached to the side walls. The compartment C is partitioned off into divisions for reception of soap, cosmetics, cologne, perfume-bottles, manicure articles, shaving utensils, wash-bowl, combs, brushes, and all appurtenances 60 applicable to toilet dressing-cases. It has a hinged lid, C', preferably provided with padded lining c' to protect the fragile articles within its separate divisions. At about the middle of said padded lining and recessed 65 therein is a looking-glass, c'. Thus, when the trunk is in the position shown in Fig. 3, by simply lifting the lid C' a complete toilet-case is presented with attached looking-glass, and without the removal of any tray or de- 70 taching any portion of the trunk.

The cover C' may be upheld at a desired inclination by any suitable device. I show linked cords 6 6 upon the cover B, adapted to engage buttons or hooks 7 7 upon the cover C', 75 that will serve such purpose; but do not wish to be understood as limiting myself to such form of fastening device.

Below the compartment C are a series of bureau-drawers. I show three in the drawings; 80 but there may be more or less without departing from the scope of my invention. The several drawers are separated from each other by means of a rigidly-attached shelf, d, that extends the full depth and width of the trunk-body, 85 forming midway supporting braces therefor. To give additional supporting strength to the trunk, I face each of these shelves with a rod or bar, d', preferably of steel, which bars are firmly secured by rivets, bolts, or the like to 90 the trunk-body. These shelves and rods perform a double function. They provide a way or

track for guiding the drawers as they are withdrawn and returned, and also serve the purpose of securely bracing the trunk-body, whereby all risk of expansion or collapse is avoided. 5 I consider this an important feature of my invention, adding great structural strength to the trunk, a quality much required in such articles, for I will observe that a trunk constructed as herein set forth can be made of 10 very large dimensions without risk of its fracture or the rupture of its contents, even when roughly handled, by reason of the strong support secured by the shelves *d* and rods *d'*. I prefer that one or more of these drawers shall 15 be partitioned off.

For the purpose of illustrating my invention I show a main undivided clothes-drawer, *D*, a partitioned drawer, *D'*, adapted to contain under-clothing, hat-box, hosiery, &c., and a 20 drawer, *D''*, containing divisions for shirts, collars, cuffs, scarfs, gloves, &c. The drawers *D D' D''* are of the usual form, having bottom, sides, front, and rear, such members being indicated by numerals 1 2 3 4, the front 4 being 25 provided with handles 5, for an obvious purpose.

It will be readily understood that when the trunk is stood on end and opened, as shown in Fig. 4, and the locking-bar is removed said 30 drawers *D D' D''* can be withdrawn outwardly. (See dotted lines.)

E is a locking-bar having a hooked upper end, *e*, its opposite end, *e'*, adapted to fit snugly within a socket, *e''*, located at the center near 35 the edge of the end *B'* of the trunk. Said bar is slotted at *e''* for reception of staple *e'*, (shown in the drawings extending outwardly from strip *e*,) a small padlock, as *e''*, holding the bar in position. Besides keeping the drawers in position 40 within the body of the trunk, the bar at the same time, by means of its hooked end *e*, holds down the lid *C'* of the dressing-case, as said hooked end is made long enough to pass over the upper edge of the strip *e*, and from 45 thence extends a required distance over and upon the front upper surface of the lid *C'*. When it is desired to leave said lid open and nevertheless have the drawers locked, the same can be done by adjusting the bar *E*, as before 50 described, without passing the hooked end over the lid *C'*.

The hinged cover *B*, which, when the trunk is entirely closed, forms one of its ends, has upon its side edges outer projecting metal 55 flanges, *b*, which are returned downwardly a short distance away from the edges proper, 8, of said trunk end, thus leaving an intermediate annular space, *b'*, extending the full length of the side edges of said trunk end *B*. The front and back proper of the trunk-body 60 extend a little distance beyond the upper surface of the toilet-compartment, uprising beyond its cover, thus forming projections, as 9, which projections, when the end *B* is closed 65 down, respectively fall within the annular recesses *b'*, making a tight joint and preventing displacement of these connected parts. The

trunk-cover *A'* is also provided with extending metal flanges 10, 11, and 12. The former overlaps the front edge, 13, of the trunk. The 70 flange 11 in like manner overlaps the edge of the end *B'*, while the opposite flange, 12, passes outwardly over the edge of the hinged portion *B* and firmly keeps it from lateral displacement. The trunk-cover is mainly appropriated 75 and fitted up as an escritoire. The lower portion is partitioned off to form a bin, 14, as a clothes and shoe department.

The rear of the cover is divided off its full length as a receptacle, 15, for umbrellas and canes. To prevent such articles from rattling or moving about during transit, one or more straps of elastic webbing, 16, are inserted across said receptacle, and it will be readily understood that if one or more of such articles 85 are inserted behind said elastic straps they will be held stationary by means of the resiliency of the webbing.

The cover *A'* has interiorly a compartment, *F*, which is subpartitioned into divisions *f f*, 90 for holding books, &c. Above these is an extensible drawer, *F'*, for containing paper, envelopes, and the like, which drawer, when pulled out, forms a rest for the cover *G*, which, when folded up in such position, comprises 95 an inclined writing-table. Above the drawer *F'* the remainder of the interior of the trunk-cover is subdivided into pigeon-holes 17, one of which at about the center of the lowermost part is appropriated for an inkstand, said 100 subdivision being provided with pen and pencil rack 18.

The cover *G* is hinged above the stationery-drawer *F'*, extending therefrom downwardly over said drawer and over the bin 14 to a 105 strip, 19, and is provided with a lock, 20, whereby it is secured to said strip. It is further provided with buttons or clasps 21, as a further protection to keep it engaged with said strip and to prevent warping. As before 110 described, when the cover *G* is lifted up and the drawer *F'* is pulled outwardly, said cover will rest upon the drawer and form an inclined writing-table.

The pigeon-holes 17 are also adapted to be 115 closed up by means of a cover, *II*, hinged to the trunk-cover at 21'. The cover *II* has at its lower end a detent-plate, 23, which, when said cover is folded down over the face of the 120 pigeon-holes, engages with a spring-pressed latch, 22. Said latch is operated by the sliding drawer *F'*, and, as plainly shown in Fig. 6 of the drawings, the latch 22 and detent 23 are automatically engaged and released as the 125 drawer is slid to and fro within its casing. The several pigeon-holes 17 are adapted and intended to hold letters and files of papers in a flat position in larger or smaller quantities. For the purpose of keeping such files in position and to prevent them from moving about 130 during transit said pigeon-holes are provided with spring-pressed slabs *f'*, which are normally kept down toward the bottom of the several pigeon-holes. The papers are slid

under said slabs, and are thereby clipped. (See detail, Fig. 8.)

I will observe that when in describing compartments and divisions of the device I employ the words "top" and "bottom" my meaning is to refer to the position of the trunk and its cover standing on end, as shown in Figs. 2, 3, 4.

Having now fully described my invention, 10 what I claim is—

1. A convertible trunk the body and hinged cover of which are subdivided into compartments and having one of its ends, B, hinged to the rear wall of the frame to form a swinging lid when the trunk is stood up on its opposite end, B', as and for the purpose intended, substantially as described.

2. A compartment-trunk the body of which is provided with sliding drawers and a toilet-section, said section having a hinged lid, in combination with locking-bar E, one end of which is adapted to fall within a socket, e², of the permanently-attached end B', the opposite end of said bar being turned over to form a hook, e, as and for the purpose intended, substantially as described.

3. A convertible trunk having rigid shelves extending interiorly the full width and breadth of its frame, in combination with metal rods 30 facing said shelves, the ends of which rods pass through the front and rear walls of the trunk-frame and are securely bolted thereto, whereby the trunk is securely braced laterally and transversely and is prevented from expansion and collapse, substantially as described.

4. A convertible trunk the cover of which is divided into compartments arranged as an escritoire, consisting, essentially, of the following elements: a series of pigeon-holes, 17, below which is a sliding drawer adapted when withdrawn from its casing to support the rearward portion of a hinged cover, G, when lifted up over said drawer, and thereby form a writing-table having a continuous unbroken 45 obliquely-inclined surface, as and for the purpose intended, substantially as described.

5. In a compartment-trunk, the cover A', partitioned off at its rear end to form an umbrella-case, 15, said division provided with 50 strips of webbing 16, the remainder of said cover being divided into clothes-bin 14, book-divisions F f, drawer F', and pigeon-holes 17, said pigeon-holes and partitions adapted to be closed by hinged covers H and G, substantially as described.

6. A convertible trunk the cover of which is provided with a series of pigeon-holes, said pigeon-holes having a hinged cover adjusted to fold over and close their free open ends, 60 said pigeon-hole cover supplied at its lower end with a detent-plate, in combination with a coincident latch operated by a drawer arranged to slide to and fro within casing below said pigeon-holes, whereby said pigeon-hole cover and latch will be automatically intermeshed and released, as and for the purpose intended, substantially as described.

CLARENCE D. HESS.
